UNITED STATES PATENT OFFICE.

WILLIAM BLACKMORE, OF CLEVELAND, OHIO, ASSIGNOR TO THE NATIONAL MALLEABLE CASTINGS COMPANY, OF CLEVELAND, OHIO.

COUPLING-POCKET FOR RADIAL-DRAFT GEARS.

1,278,838.

Specification of Letters Patent. Patented Sept. 17, 1918.

Application filed May 24, 1913. Serial No. 769,567.

To all whom it may concern:

Be it known that I, WILLIAM BLACKMORE, a citizen of the United States, residing at Cleveland, Cuyahoga county, Ohio, have invented a new and useful Improvement in Coupling-Pockets for Radial-Draft Gears, of which the following is a specification, reference being had to the accompanying drawings, in which—

10 Figure 1 is a plan partly in section of my improved construction; Fig. 2 is an elevation partly in section thereof; Fig. 3 is a section on lines III—III of Fig. 2 and Fig. 4 is a section on lines IV—IV of Fig. 2; and 15 Fig. 5 is an elevation partly in section showing my improvements as used with a Master Car Builders' coupler,

My invention relates to radial draft gears and provides an improved form of attachment of the coupler shank to the draft member or coupler shank extension. It is applicable alike to couplers having specially constructed shanks and to those of the Master Car Builders' type.

20 Referring to the drawings, 2 indicates the coupler shank extension or draft member, the forward end of which terminates in a pocket portion 3, adapted to receive the shanks of different styles of couplers. The 25 numeral 4 indicates an automatic coupler of any suitable type, having a shank 5 specially constructed for insertion into the pocket portion 3. The shank 5 has the usual liner block portion 6 with vertically-extending 30 rivet holes 7, and the usual transverse slot 8 just forward of the liner block. Upon the bottom and top of the coupler shank are integral ribs 9 adjacent to the head of the coupler. These ribs 9 are adapted to center the 35 shank of the coupler vertically within the pocket of the shank extension, since the mouth of the pocket must necessarily be of sufficient vertical depth to receive the liner block 6, which is normally deeper than the 40 shank 5. The coupler shank is inserted into the pocket and pushed rearwardly until the forward edge of the pocket abuts against the head of the coupler and forms a buffering surface therewith. The key 10 is then inserted laterally through the apertures 11 and 45 pocket portion of the coupler shank extension, which register with the slot 8 in the coupler shank. Bearing blocks 12 are inserted immediately above and below the coupler shank, just in front of the forward 50

edges of the liner block and register in slots 13 formed in the side walls of the pocket. The key 10, after insertion, is held in position by the bolt 14, which is passed through one of the usual rivet holes 7 of the 55 coupler shank 5 and bears in a notch on the rear side of the key 10, and so prevents its lateral removal. Underneath the head and the nut respectively of the bolt 14, and on the exterior of the pocket 3, are securing members 15, which have formed integral with their forward ends inwardly-extending dowels 16, which pass through openings in the upper and lower walls of the pocket and into registering apertures in the bearing 70 blocks 12.

When the bolt 14 is placed in position with the securing members thereon, and the nut is screwed home, the bolt, the key 10 and the bearing blocks 12 are firmly held in position. 75 This avoids having the keys and bearing blocks project outwardly from the sides of the shank extension for the purpose of receiving additional fastening means, and enables them to be cut off flush with the sides 80 of the pocket portion of the shank extension.

I have shown in Fig. 5 my device as applied to the shank of an ordinary M. C. B. coupler. With a coupler of this character the attachments at the rear end are made in 85 precisely the same way as I have described with regard to the construction shown in Figs. 1, 2, 3 and 4. The M. C. B. coupler, however, has no vertically centering ribs, and in order to properly center the coupler 90 shank in the coupler pocket at its forward end loose filler pieces 9½ are provided as a substitute for the integral ribs 9 shown in Figs. 2 and 4.

Various modifications may be made in the 95 constructions which I have shown and described herein, without departing from my invention.

What I claim is:

1. A draft gear having a pocket for reception of the liner block of a coupler shank, slots in the walls of the pocket for the reception of bearing blocks, the said bearing blocks in their greatest dimension not being longer than the width of the pocket and being adapted to engage the forward edges of the liner block, and means coöperating with the pocket for preventing lateral movement of the bearing blocks.
2. A draft gear having a forwardly ex- 110

- tending pocket adapted to receive a coupler, a coupler having its shank rigidly secured therein, the head of said coupler having a shouldered engagement with the forward edges of said pocket, the inside vertical depth of said pocket being greater than the depth of the coupler shank, and ribs between the horizontal faces of the coupler shank and upper and lower walls of said pocket adapted to hold the coupler in a substantially horizontal position.
3. A draft gear having a pocket for reception of a coupler shank, a plurality of keys engaging the coupler shank and the pocket for securing the coupler shank in the pocket, a vertically-extending bolt and securing members attached thereto, said bolt and securing members being adapted to hold the keys against horizontal movement.
4. A draft gear having an integral forwardly extending pocket having horizontal top and bottom walls adapted to receive differently dimensioned shanks of car couplers, a coupler adapted to be inserted into said pocket from the forward side, means removable with the coupler between said shank and the walls of said pocket, adapted to hold said coupler in substantially horizontal position within the pocket, and means for fixedly securing the coupler in said pocket.
5. A draft gear having a forwardly extending pocket adapted to receive a coupler, a coupler having its shank secured therein, the head of said coupler having a shouldered engagement with the forward edges of said pocket, the inside vertical depth of said pocket being greater than the depth of the coupler shank, and ribs on said shank adjacent to the head adapted to engage the upper and lower walls of said pocket to hold the coupler in substantially horizontal position.
6. A draft gear having a pocket for the reception of the liner block of a coupler shank, and having a buffering bearing against the coupler forward of the liner block, slots in the walls of the pocket for reception of bearing blocks, the said bearing blocks being adapted to engage the forward edges of the liner block, a horizontal key member insertible through the walls of the pocket and through the coupler shank, and means in the central vertical plane of the pocket and coupler shank for preventing lateral movement of the bearing blocks and the key member.

WM. BLACKMORE.
